UNITED STATES PATENT OFFICE.

JOSEPH C. FIELD, OF ORANGE, NEW JERSEY, ASSIGNOR TO WESTERN ELECTRIC COMPANY, INCORPORATED, OF NEW YORK, N. Y., A CORPORATION OF NEW YORK.

SUPERVISORY SYSTEM.

Application filed October 18, 1921. Serial No. 508,443.

To all whom it may concern:

Be it known that I, JOSEPH C. FIELD, a citizen of the United States, residing at Orange, in the county of Essex, State of New Jersey, have invented certain new and useful Improvements in Supervisory Systems, of which the following is a full, clear, concise, and exact description.

This invention relates to control and supervisory systems, and particularly to such systems in which switches or other apparatus may be remotely controlled and supervised.

The invention is particularly adapted for use in connection with circuit controlling apparatus employed on power lines where it is desired to control a number of distant circuits from a central station.

An object of the invention is to provide a system of this character which includes a minimum number of operating elements, and which is reliable and rapid in operation.

Another object of the invention is to provide means for indicating at the central station the condition of the apparatus at a remote station.

In this system there are a central or controlling station and a remote station in or near which the apparatus to be controlled is situated. Each of these stations is provided with a transmitting and a receiving rotary distributor such as is commonly used in printing telegraph systems. These distributors may be of the type disclosed in Patent No. 1,311,915 granted to P. M. Rainey, August 5, 1919. The receiving distributor at each station operates synchronously with the transmitting distributor at the other station, the brush arm of each of the distributors, which is frictionally mounted on a continuously rotating shaft being adapted to be arrested periodically and then released automatically through the instrumentality of the other distributor. The transmitting distributor at the control station transmits controlling impulses which are selectively distributed by the corresponding receiving distributor to electromagnetic devices through which the desired switch controlling or other remote operation is performed. At the remote station the controlled apparatus mechanically operates switches which supply current to be transmitted in impulses by the transmitting distributor at the remote sta-

tion, which impulses are selectively distributed by the receiving distributor at the control station to electromagnetic devices, through which signals are operated indicating the condition of the apparatus at the remote station. The system may be considered as having two parts. One part transmits impulses to the mechanism to be controlled, and the other part transmits impulses generated at the controlled mechanism to operate the supervisory apparatus at the central station.

Another object of the invention is to provide means for repeating the controlling impulses at regular intervals, so that if the controlling means does not immediately operate at the local station, succeeding impulses will insure its operation if such is possible and with little delay.

Another feature of the invention is the manner in which synchronism is secured between the transmitting and receiving distributors of each set. As has been said, the distributors are in two pairs. These pairs do not operate simultaneously but successively. That is to say, after a full revolution of one set of distributor arms, they are locked, and, as they near the completion of a revolution, release the other set of distributor arms which go through a similar cycle of operations to release the first set. This operation is continually repeated.

Other objects and advantages of the invention will become apparent from the following detailed description taken in connection with the accompanying drawing which shows diagrammatically one embodiment of the invention.

Referring to the drawing, A represents the central station from which it is desired to control a series of electrically operated devices at a remote station B. The electrically operated devices disclosed here consist of power switches of which 1 and 2 are typical.

In order to indicate whether switches 1 and 2 are open or closed, a number of supervisory lamps 3, 4, 5 and 6 are provided at the central station A, of which 3 and 4 show the position of power switch 1, and 5 and 6 show the position of power switch 2. Connecting stations A and B is a line 7, which is the only metallic connection between these stations.

At station A there is provided a plurality of manually operated controlling switches of which 8 and 9 are typical, and which correspond to the power switches 1 and 2, respectively.

Two sources of current 10 and 11 having opposite poles grounded are each associated with the switches 8 and 9 in such a manner that the moving element of these switches 10 may be connected with negative or positive current by operating them in opposite directions. The moving elements of switches 8 and 9 are associated with segments of a rotary transmitting distributor 12 by means 15 of which current impulses are successively transmitted to the line 7.

At the remote station B a rotary receiving distributor 13 is provided which, in a manner hereinafter described, is operated in synchronism with the transmitter 12. Impulses from the line 7 are transmitted to polarized relays 14 and 15 which correspond to the switches 8 and 9 and the power switches 1 and 2 respectively, through the 20 collector ring 42, brush arm and segments of receiving distributor 13. The polarized relay 14 operates to energize or deenergize the electromagnet of the power switch 1 to open or close it, depending upon the polarity of 25 the current impulse transmitted to the polarized relay. Likewise the polarized relay 15 operates or releases power switch 2, depending upon the polarity of the impulses transmitted thereto.

30 Power switches 1 and 2 are provided with mechanically operated switches 16 and 17 which have alternate contacts connected to sources of current 18 and 19 of opposite polarity. The power switches are mechanically connected with the moving elements of 35 these switches 16 and 17 so that when the power switches open or close they cause switches 16 and 17 to connect with current of one or the other polarity.

40 The moving elements of the switches 17 and 16 are electrically connected to successive segments of a rotary transmitting distributor 20 through the brush arm and collector ring 47 of which electrical connection is made with the line 7.

45 A corresponding rotary receiving distributor 21 is located at the central station A and is connected through its collector ring 49 and brush arm to the line 7. Polarized relays 22 and 23 are connected to successive segments of the receiver 21 so that the impulses transmitted from the sources of current 18 and 19, through the 50 switches 16 and 17 are transmitted to the polarized relays 22 and 23, respectively. It will be evident that additional power switches, such as 1 and 2, may be connected in the circuit, in which case, corresponding 55 polarized relays such as 14, 15 and 22, 23, control switches, such as 8 and 9, and

switches such as 16 and 17, will be associated with corresponding segments of distributors 13, 21, 12 and 20, respectively, lead wires being shown for this purpose.

When the power switch 1 is in its open 70 position, as shown in the drawing, positive current is transmitted through the segment 55 of the distributor 20 as the brush arm thereof revolves, through the line 7, through the collector ring 49 and brush arm of receiver 21 to the corresponding segment on the receiver 21 and through the polarized relay 23 to ground. The armature of the relay 23 operates to close a circuit through the lamp 3 to a suitable source of current 80 thus lighting the lamp and showing that the power switch 1 is open.

When the power switch 1 is closed, negative current is supplied from the battery 19 in a manner, similar to that before described, to operate the polarized relay 23 in its opposite direction, thus illuminating the lamp 4 and indicating at the station A that the power switch 1 is in its closed position. Similar circuits are established for the 90 lamps 5 and 6 by the power switch 2.

As above described, the system comprises two parts, one by means of which impulses are transmitted from the central station through the distributors 12 and 13 to the power switches at station B, and the other by means of which impulses under the control of the power switches 1 and 2 are transmitted to the central station A through the distributors 20 and 21 to control the supervisory lamps. Each of the distributors is arranged to have its brush arm stopped once per revolution and then released automatically due to the passage of the brush carried by the brush arm over the segments to which the release magnet of the other distributor is connected, thereby causing the brush arm thereof to be released. In the normal operation of the system, the brush arm of each of the distributors is arrested periodically and subsequently released by the other distributor located at the same station, thus providing a continuously operating system.

110 With the switches 8 and 9 in the position shown in the drawing, relays 14 and 15 at station "B" are also in the position shown in the drawing. The energizing circuits of the operating magnets of power switches 1 and 2 are thereupon open, in turn causing the circuits controlled by these switches to be open. When it is desired to operate either of these switches 1 and 2, it is necessary to actuate the corresponding switch 8 or 9 for connecting the negative source of current 11 with the segment of the distributor allotted to this particular switch. For instance, should it be desired to close switch 1, switch 8 is moved to engage its 115 upper contact whereby the negative source 120

125 130

of current is connected to segment 51 of distributor 12. The distributor brush in passing over segment 51, causes the transmission of a corresponding impulse to station "B" over the line conductor 7. This impulse, upon being received at station "B" is caused to flow, upon the passage of the brush of distributor 13 over segment 52, through the windings of relay 14. The passage of a negative impulse through the windings of relay 14, causes the reversal of the armature thereof, thereby causing the completion of an energizing circuit for the operating magnet of power switch 1, extending from battery 54 through the winding of the operating magnet of power switch 1 and contact 53 and armature of relay 14 to ground. Power switch 1 is then operated for bridging the terminals of the power circuit controlled thereby, as well as causing the opening of switch 16 and the closure of its upper contact. The operation of switch 16 in this manner establishes an energizing circuit for relay 23 at station "A" upon the passage of the brush of distributor 20 over segment 55 and the passage of the brush of distributor 21 over segment 56 to which the windings of relay 23 are serially connected. The impulse traversing the windings of relay 23 for the condition just described being of a negative polarity, causes the reversal of the armature of relay 23 for breaking the local circuit of lamp 3, and establishing a circuit for lamp 4, which indicates that the power switch 1 has been closed. The operation of the power switch 2 and other similar power switches associated with other segments of the distributors is similar to the operation of power switch 1.

It is necessary that these two parts of the system be operated successively and not simultaneously, in order to avoid a confusion of the impulses on the line 7. The successive operation of the two sets of distributors is accomplished by successively energizing the release magnets of one set through circuits established by the other set. The circuit for releasing the distributors 12 and 13 is as follows: from the source of current 10, conductors 24 and 25, release magnet 39 of distributor 12, conductor 26, segment 35 of distributor 21, through the brush arm, segment 40, conductor 27, segment 28, brush arm and collector ring 41 of distributor 12, conductor 29, line 7, collector ring 47, brush arm and segment 36 of distributor 20, conductor 30, segment 43, brush arm and segment 44 of distributor 13, winding of release magnet 45 to ground. Release magnets 39 and 45 are energized in series, releasing distributors 12 and 13 simultaneously which make one revolution. Just before completion of this revolution, the brush arms contact with segments 31 and 32 respectively establishing a circuit from source

of current 10, conductor 24, through the release magnet 46 of distributor 21, conductor 33, segment 31, brush arm and collector ring 41 of distributor 12, conductor 29, line 7 to the collector ring 42 of distributor 13, brush arm, and segment 32 of distributor 13, release magnet 48 of distributor 20 to ground. Release magnets 46 and 48 are energized in series thus simultaneously releasing distributors 20 and 21 which complete a single revolution, and then release the distributors 12 and 13. The alternating operation of the distributor sets provides a means for sending a continuous succession of impulses from one station to the other, insuring the operation of the controlling polarized relays 14, 15, 22 and 23. It may happen that such a relay fails to operate on the first revolution of the distributors but due to the repetition of operation of the distributors, a relay which may have failed to operate will operate subsequently.

Switch 1 is shown as a simple electrically operated power switch. Switch 2 is shown as a power switch equipped with underload and overload release relays 49 and 50 respectively. It will be noted that should switch 2 be automatically released due to relays 49 or 50, such release will be immediately indicated by the illumination of lamp 5. When it is desired to discontinue the operation of the system, the switch 57 may be opened for disabling the energizing circuit of release magnet 39 of distributor 12, whereupon the brush arm of distributor 12 after completing its cycle of rotation will be stopped until the subsequent closure of switch 57. Likewise the other distributors will be stopped.

What is claimed is:

1. In a system for remote control and supervision, a central controlling station and a remote station, a plurality of electromagnetically controlled switches at the remote station, a supervisory device corresponding to each switch and located at the central station, a rotary distributor set comprising a transmitter and a receiver to transmit electrical impulses selectively to the switches, a rotary distributor set comprising a transmitter and a receiver to transmit electrical impulses selectively to the supervisory devices from the switches, and holding and releasing means for each distributor, transmitter and receiver, such holding and releasing means for each set being connected electrically in series, and said means for one set being controlled by the other set.

2. In a system for remote control and supervision, a central controlling station and a remote station, a line associating the stations, a plurality of electromagnetically controlled switches at the remote station, a supervisory device corresponding to each such switch and located at the central station, a

rotary distributor set comprising a transmitter and a receiver to transmit electrical impulses selectively to the switches, a rotary distributor set comprising a transmitter and 5 a receiver to transmit electrical impulses selectively to the supervisory devices from the switches, and electromagnetically operated holding and releasing means for each distributor, transmitter and receiver, such 10 means for each set being connected electrically in series, and said means for one set being controlled by the other set.

3. In a system for remote control and supervision, a central station, a remote station, 15 a plurality of electromagnetic devices having normal and alternate positions at said remote station, a pair of signaling indicators at the central station for indicating the two positions of each of said devices, a 20 key at the central station for each of said devices having two positions, a single conductor interconnecting said stations, a pair of transmitting and receiving distributors at each station, said keys in one position applying one electrical condition to the transmitting distributor segments and in the other position applying another electrical condition, relays at the remote station controlling the position of said devices operated 25 by the receiving distributor in accordance with the positions of the actuated keys at the central station, switches operated by the actuated devices to apply different electrical conditions to the transmitting distributor 30 segments at the remote stations, relays at the central station operated by the receiving distributor thereat in accordance with the devices actuated at the remote station, and means actuated by the transmitting and receiving distributors near the end of their travel for starting the other pair of distributors.

4. In a system for remote control and supervision, a central station, a remote station, 45 a plurality of devices at the remote station having normal and alternate positions, a pair of indicators at the central station for indicating the positions of each of said devices, a key at the central station for each of said devices, a single conductor interconnecting said stations, a transmitting and receiving distributor at each station, said keys applying positive or negative po-

tential to the transmitting distributor at the central station depending upon the position 55 of said keys, polarized relays at the remote station controlling the position of said devices operated through the receiving distributor in accordance with the polarity of the potential applied to said transmitting distributor by said keys, switches operated by the actuated devices to apply positive or negative potential to the transmitting distributor at the remote station, polarized relays at the central station operated by the 60 receiving distributor thereat in accordance with the devices actuated at the remote station, and release magnets actuated by the transmitting and receiving distributors near the 65 end of each revolution for starting the other pair of distributors.

5. In a system for remote control and supervision, a central station, a remote station, a plurality of devices at the remote station having two positions, a pair of signaling 70 lamps at the central station corresponding to each of said devices for indicating the positions of said devices, a key at the central station for each of said devices having two positions, a single conductor interconnecting 75 said stations, a transmitting and a receiving distributor at each station, polarized relays at the remote station for controlling the operation of said devices, said keys applying positive or negative potential to said polarized relays through the transmitting distributor at the central station, the conductor joining said stations and the receiving distributor at the remote station, switches operated by the actuated devices, polarized 80 relays at the central station for controlling the lighting of said signaling lamps, said switches applying positive or negative potential to said polarized relays through the transmitting distributor at the remote station, the conductor joining said stations and the receiving distributor at the central station, and means controlled by the transmitting and receiving distributors near the end 85 of each revolution for starting the other pair 90 of distributors.

In witness whereof, I hereunto subscribe my name this 11th day of October A. D., 1921.

JOSEPH C. FIELD.
